UNITED STATES PATENT OFFICE.

MICHAEL HALLANAN, OF NEW YORK, N. Y.

HOOF-PAD.

SPECIFICATION forming part of Letters Patent No. 660,427, dated October 23, 1900.

Application filed December 1, 1899. Serial No. 738,799. (No model.)

To all whom it may concern:

Be it known that I, MICHAEL HALLANAN, a citizen of the United States, and a resident of the city of New York, borough of Manhattan, in the county and State of New York, have invented a new and Improved Hoof-Pad, of which the following is a full, clear, and exact description.

The principal purpose of this invention is to so construct hoof-pads of leather and rubber as to prevent the separation of the parts during the use of the pad. In the practical use of hoof-pads constructed of a composite of leather and rubber it has been found that the rubber is frequently knocked off the pad, thus of course destroying the pad. By means of my invention the rubber is more securely held to the leather and the necessity for sewing is to a large extent done away with, cement sufficing in most cases.

This specification is the disclosure of one form of my invention, while the claims define the actual scope thereof.

Reference is to be had to the accompanying drawings, forming a part of this specification, in which similar characters of reference indicate corresponding parts in all the views.

Figure 1 is an under side view of the pad in use. Fig. 2 is a top view of the rubber section or the pad proper, and Fig. 3 is a sectional view on the line 3 3 of Fig. 1.

The pad to which my invention is applied is here shown to comprise a leather backing-plate *a* of the marginal form indicated in Fig. 1 and a rubber section or pad proper, *b*, secured to the under side of the backing-plate *a* and having a portion *b'* cutaway to receive the shoe *c*, as shown, it being understood that the shoe is nailed through the leather plate *a* into the hoof and that the pad proper, *b*, is held in position by its connection with the backing-plate. At the front edges of the widened heel portion of the pad *b* and directly adjacent to the cut-away part *b'* thereof projections *b''* are formed on the pad *b*, and the horseshoe *c* has its heel portions reduced, as indicated by dotted lines at *c'*, so that the reduced heel portions of the shoe may lie under the projections *b''*, thus clamping these portions of the pad *b* in position. As shown in Fig. 1, the nail-holes of the shoe, at the heel thereof, are arranged directly adjacent to the reduced

portions *c'*, so that the heel portions of the shoe are held firmly at this point, so as to press firmly on the projections *b''* of the pad *b*. Now for the purpose of firmly securing the pad *b* to the backing-plate *a* I construct the pad and back-plate with interengaging surfaces or members, whereby to resist the tendency of the rubber pad to shift or work edge-wise from its position on the back-plate, and in carrying out this invention I so dispose the engaging surfaces as to offer a resistance in all directions to the strains on the pad. As shown best in Fig. 2, the pad is provided with a number of transverse ribs or corrugations *d*, extending substantially throughout the width of the pad at the heel and forwardly to a point just rearward of the projections *b''*, before referred to. The forward portion of the pad *b* is formed with a number of shorter corrugations *d'*, situated at the edges of the pad and disposed approximately in radial position with respect to the center of the before-mentioned forward portion of the pad. This forward portion of the pad has its middle or central part plane to lie snugly against the back-plate *a*, forming a broad cementing-surface. Extending continuously throughout the pad *b*, at the margins thereof, is a groove *d''*, which forms a small flange around the margin of the pad. This groove *d''* is situated at the ends of the ribs or corrugations *d'*, and the depressions or grooves formed by these ribs run into the marginal groove *d''*. The leather backing-plate *a* is formed with corrugations and grooves to match those of the pad, in the manner shown in Fig. 3. In this view it will be seen that the back-plate *a* is formed with transverse ribs *a'* at its heel portions, forming grooves on the under side of the plate, which match with the ribs *d* and with shorter approximately radial ribs *a''* at its front portions, forming grooves on the under side of the plate, which match with the ribs *d'*. The plate *a* is also formed with a continuous groove *a''* in its top face, such groove producing a rib on the bottom of the plate *a*, which rib fits into the groove *d''* of the pad. The two sections of the device are so formed that their several ribs and grooves will match exactly with each other. The parts *a* and *b* being thus constructed, they are set together, as shown, and cemented in the usual manner.

The result of this construction is that the several interengaged ribs and grooves resist the strains on the pad and prevent the separation of the pad from the back-plate *a*. It should be understood that in the use of the pad the strain thereon is to a large extent in the plane of the pads. This tends to disrupt the securing means and gives a tendency of the pad to creep on the back-plate. Therefore in my invention, which prevents the movement of the pad on the back-plate, the cement between these two parts cannot be broken and the pad will remain intact. By providing the marginal groove *d*² for the pad, forming the small marginal flange, and the corresponding formation *a*³ of the back-plate I insure the snug and hermetic engagement of the edges of the pad with the back-plate and constitute what is practically a seal at the edges, thus insuring the security of the pad at its edges, which, it should be understood, is a very important point, for it prevents a single part of the edge of the pad from becoming detached from the back-plate, in the event of which dirt and other material would enter between the pad and the back-plate, to their injury.

Reference to Fig. 3 will show that the heel portion of the parts *a* and *b* is set slightly lower than the other portion of the pad, thus placing the heel of the pad out of contact with the heel of the hoof of the horse, which heel is indicated by the dotted lines in the figure referred to. This affords a measure of additional resiliency at the heel of the pad and eases the step of the horse. It is clear that the pad being disposed, as in Fig. 3, with its heel out of contact with the hoof will form a cushioned portion which as the horse treads will first engage the ground and in yielding will tend to break the force of the blow attending the descent of the horse's hoof.

Having thus described my invention, I claim as new and desire to secure by Letters Patent—

1. A hoof-pad, comprising a pad proper of rubber, and a backing-plate of leather, formed with interengaging ribs and grooves on their opposing faces, and being cemented at such ribs and grooves, the ribs and grooves of the heel portions of the pad and back-plate being disposed transversely and extending substantially throughout the width thereof, and the ribs and grooves at the front portions of the pad and backing-plate being disposed in an essentially radial position from the center of such front portions.

2. A hoof-pad, formed in two parts cemented together and having interengaging formations including a marginal sealing rib and groove.

3. A hoof-pad, formed of a rubber pad proper, and a leather backing-plate, provided with interlocking ribs and grooves, and being cemented together at such points, and the pad and back-plate having their margins formed with additional interlocking ribs and grooves producing a seal at the edges of the pad, for the purpose specified.

4. A hoof-pad, comprising a backing-plate, and a pad proper held thereto, said parts having mating ribs and grooves ranging transversely, and additional ribs and grooves at different angles to the first-named ribs and grooves.

5. A hoof-pad, comprising a front or main portion adapted to lie firmly against the hoof, and a rear or heel portion set away from the hoof normally out of contact therewith, such portion extending throughout the width of the pad, and being yielding to cushion the tread of a horse.

6. A hoof-pad, having a main or front portion, and a rear or heel portion, the upper surface of which latter portion is situated in a plane below that of the main or front portion and extends throughout the width of the pad so that when the main or front portion of the pad is engaged with the hoof the heel portion will be set away therefrom, for the purpose specified.

7. A hoof-pad, comprising a pad proper, and a stiff backing-plate laid thereon and to which the pad is secured, the backing-plate being adapted to be attached to the hoof, and the backing-plate and pad being provided with interengaging formations on their engaging faces, by means of which formations independent edgewise movement of the pad and plate is prevented.

8. A pad comprising a stiff upper or back plate and a yielding pad proper on the under surface thereof, and the back-plate and pad proper having interengaging formations preventing relative edgewise movement of the parts.

In testimony whereof I have signed my name to this specification in the presence of two subscribing witnesses.

MICHAEL HALLANAN.
